UNITED STATES PATENT OFFICE

168,253

TEXTILE FABRIC

Paul P. Chiarelli, Brooklyn, N. Y., assignor to Chicopee Mills, Inc., a corporation of New York

Application August 9, 1952, Serial No. 29,961

Term of patent 14 years

(Cl. D92—1)

To all whom it may concern:

Be it known that I, Paul P. Chiarelli, a citizen of the United States, residing at Brooklyn, in the county of Kings, State of New York, have invented a new, original and ornamental Design for a Textile Fabric, of which the following is a specification, reference being had to the accompanying drawing, forming a part hereof in which the figure is a plan view of a textile fabric showing my new design.

I claim:

The ornamental design for a textile fabric, as shown.

PAUL P. CHIARELLI.
